UNITED STATES PATENT OFFICE.

JESSE G. VINCENT, OF DETROIT, MICHIGAN, ASSIGNOR TO BURROUGHS ADDING-MACHINE COMPANY, OF DETROIT, MICHIGAN, A CORPORATION OF MICHIGAN.

KEYBOARD MECHANISM FOR ADDING-MACHINES.

1,002,341.

Specification of Letters Patent. Patented Sept. 5, 1911.

Application filed January 22, 1907. Serial No. 353,492.

To all whom it may concern:

Be it known that I, JESSE G. VINCENT, a citizen of the United States, residing at Detroit, in the county of Wayne and State of Michigan, have invented certain new and useful Improvements in Keyboard Mechanism for Adding-Machines, of which the following is a specification:

The present invention relates more particularly to what are commonly known in the art as "flexible" key-boards, that is to say key-boards in which after depression of an amount key in any row or bank another key in the same bank can be depressed causing the previously depressed key to be released.

One object of the invention is to overcome difficulties attendant upon the use of elongated detent devices, one for each row or bank of keys, such an arrangement requiring practically unattainable accuracy in the manufacturing and assembling of parts. In carrying out the present invention no such elongated detent devices are employed but the keys of a bank or row are severally connected with detent pieces which are compactly grouped for coöperation with a latching device.

Another object of the present invention is to provide simple and effective means in connection with a key-board of the character described for positively locking the keys immediately an operation of the machine starts. Thus where certain keys have been depressed and the machine starts to operate no other keys can be depressed until the operation is over. Furthermore the detents of depressed keys will be locked so that the effect to be produced in an operation of the machine as determined by the depression of certain amount keys cannot be altered after an operation of the machine has started, either by depressing other amount keys or otherwise releasing or rendering ineffective the detent devices of the depressed keys.

With these and incidental objects in view the invention consists in certain novel features of construction and combinations of parts the essential elements whereof are recited in the appended claims and a preferred form of embodiment of which is specifically described hereinafter and fully illustrated in the accompanying drawings.

Of said drawings Figure 1 represents

partly in left-side elevation and partly in section a key-board of the character employed in the well-known Burroughs adding and listing machine, together with certain key-releasing devices of such machine, the improvements of the present invention being shown embodied in the structure; Fig. 2 represents a portion of such a key-board in top plan view with the upper key-board plate removed and certain parts broken away to disclose others beneath them in section; Fig. 3 is a view similar to the upper left-hand portion of Fig. 1, illustrating a changed relation of parts due to depression of one of the keys; Fig. 4 is a similar view illustrating a changed relation of parts due to an operation of the machine having been started and not completed; and Figs. 5 and 6 show different parts of the new construction detached in perspective.

While the invention is here shown as specially adapted for use with the Burroughs machine it is not necessarily so limited. For the details of this Burroughs machine reference may be had to the William S. Burroughs Patents Nos. 504,963 and 505,078, of June 12, 1893. It will suffice for the purposes of the present specification to refer specifically to only a few of the familiar parts of such a machine.

The reference numeral 291 designates the usual amount keys which are arranged in a series of rows or banks extending from front to rear of the key-board and each comprising nine keys. These keys as usual slide through slots in fixed plates 212^B and 213^B. Rows of bell crank levers 217 are as usual pivoted upon other plates 210^A set on edge below the plate 212^B and the keys bear upon these levers, being upheld by springs 284 connected at their upper ends with the plates 210^A and at their lower ends to pins or studs on the levers projecting through slots in said plates. The usual rods or wires 270 are coupled at their rear ends to said bell crank levers and at their forward ends are guided in slots of the plates 210^A, the bent ends of these rods performing the familiar function as stops to determine the extent of movement of the recording and registering parts not here shown. The bell crank levers also coöperate in the usual manner with strips or bars 214 which operate to swing the latches commonly employed to uphold the

registering racks. The bell crank levers extend as usual through slots in these strips or bars and the latter serve the further function of positively restoring the depressed keys at the end of an operation of the machine. In this connection the usual bail is arranged to rock to and fro at the rear of the machine, said bail comprising side arms 219 and a cross-rod or round bar 202 which acts upon the rear end of the strips 214. The side arms 219 are secured to a rock-shaft 207 and one or both of them will be provided with a forward extension 219^a for abutting a cross-rod 602 to limit the rearward swing of the bail by its customary springs 281. The movement of the bail in opposition to these springs is produced as usual by the action of a wipe-pawl 623^a against a roller 632₁ on the depending end of one of the side arms 219 of the bail. Said pawl is pivotally mounted on a bell crank lever 622 and normally held by a spring 688 against a lug of said lever, said spring also serving to rock the bell crank lever. The usual rock-arm 312 acts against said bell crank lever to move it in opposition to said spring 688 and carry the wipe-pawl up beyond the roller 632₁, thereby swinging the bail forward. This occurs at the end of an operation of the machine and results in releasing any depressed keys.

In carrying out the present invention the strips or bars 214 do not coöperate as in former constructions with detent pawls but the holding down of depressed keys is otherwise accomplished. The bell crank levers 217 project somewhat below the point where the rods 270 are joined to them and these depending portions of the bell cranks receive respectively studs 217^a riveted to the forward end portions of a series of strips 214^c as shown in Fig. 2. These strips are set on edge and graded in length and offset so as to lie closely together side by side. At their rear ends they are correspondingly bifurcated to slide upon a cross-rod 202^{1b}. The longest of a group of these strips is the one farthest to the right as the machine is viewed from the front, this particular strip connecting with the bell crank lever below the foremost key of the row or bank. The stud of this long strip is screw-threaded to receive a nut 217^b. The studs of the other strips require no screw-threading but merely require to be slipped into the openings of the bell cranks, for lateral displacement to the right is prevented by the long strip which is of course secured against such movement by the nut 217^b at the front end. The grouped strips are held together and against lateral movement at their rear ends through the manner of their assemblage with other parts as will be presently described. The shortest of a group of strips is the one coupled to the bell crank of the rearmost key in the row.

One of these short strips is shown in perspective in Fig. 5 and the offset portion carrying the stud is in the form of a yoke 214^c united with the strip at opposite sides of its bifurcation, the strip in this case having no forward projection of less width as in the case of the other strips.

It will be seen that with the above-described construction the rocking of any one of the bell cranks 217 by depression of the particular amount key associated with it will result in the connected detent strip being thrust rearwardly against the stress of the spring 284. The straddling of the shaft 202^{1b} by the bifurcated rear ends of the strips provides for both pivotal and sliding movements of the latter so that the slight rocking of any strip due to the arc movement of the bell crank will be taken care of. In order to economize space the slotted bars 214 hereinbefore mentioned are cut away at their rear ends as shown at the upper left-hand portion of Fig. 2 so that the group of detent strips may be brought nearer to the line of the bell crank levers 217, it being understood that the widened bifurcated rear ends of the strips project above the plane of this slotted bar as clearly shown in Fig. 3. There projects from the top edge of each strip in its widened portion a lug 214^e whose own top edge slopes rearwardly and whose front and rear edges are abrupt, extending substantially at right angles to the strip itself although preferably struck on a slight curve. When the strips are in normal position these lugs are in exact alinement. Their sloping top edges are adapted to act with a camming effect upon an anti-friction roll 228^a carried between the side arms 228^c of a latching frame which embraces the group of strips where they project above the slotted bar 214, the said side arms of this frame being yoked together at the front as shown in perspective in Fig. 6 and being pivoted upon a cross-rod 207^c so that the frame may swing up and down. Lateral shifting is prevented by spacing collars 207^d on the cross-rod 207^c between the several latching frames and the supporting plates 210^a. A spiral spring 289 connects an up-standing lug 228^e on the yoked part of each latching frame with a fixed part of the framework above and in rear thereof, said spring thus tending to depress the frame, and the rear edges of the side arms 228^c are inclined so as to coöperate with the cross-bar 202 of the key-releasing bail much as said cross-bar coöperates with the detent pawls of previous constructions.

In carrying out the present invention the bail is not permitted to swing rearwardly its full excursion as heretofore upon the pawl 263^a leaving contact with the roller 282₁, but a second roller 232₂ is mounted upon the depending part of the arm of the bail for

contact with said pawl just after the latter has passed out of contact with the roller 232 $\frac{1}{2}$. This second roller is stepped with relation to the usual roller so as to permit a certain 5 degree of movement of the bail toward its rearmost position. This latter position is determined as usual by the abutment of the projection 219^a against the rod 602 but so long as the roller 232 $\frac{1}{2}$ rests in contact with 10 the wipe-pawl said projection 219^a is kept away from the rod 602 as shown in Fig. 1. Of course it will be understood that as the wipe-pawl and bell crank lever are retracted by the spring 688 accompanying the forward 15 swing of the arm 312 which starts as soon as the machine commences to operate, the wipe-pawl will be withdrawn from contact with the stud 232 $\frac{1}{2}$ whereupon the spring 281 will draw the bail farther rearward. 20

The normal position of parts is illustrated by full lines in Fig. 1. The bail is at its intermediate position and the latching frame maintained thereby in such relation to the 25 detent strips that rearward movement of any one of the latter will cause the inclined top edge of its lug 214^e to act with a camming effect upon the under-side of the roll 228^d. Thus the latching frame will be lifted 30 against the stress of the spring 289 until the projection has passed to the rear of said roll whereupon the frame will be lowered by the spring, the roll passing down along the abrupt front side of the projection. This 35 of course prevents the detent strip from returning to its forward position (see Fig. 3) and the stop of the connected rod 270 will be held in effective position. However, any other key in the bank can be compressed 40 and its detent strip moved rearwardly with the like effect and the previously operated detent strip thereby released for restoration to normal. This will be obvious from the 45 description already given and from an inspection of Fig. 3.

During the setting up of an amount on the key-board the restoring or key-releasing bail 202-219 remains at the above-described intermediate position but just as soon as the 50 arm 312 starts forward as a result of applying power to operate the machine said bail is moved farther rearward by its spring 281 in the manner hereinbefore described. The consequent retreat of the rod or bar 55 202 from the inclined rear edges of the side arms of the latching frame permits the latter to be depressed by its spring 289 so that the roll 228^d is carried down along the abrupt rear edges of the lugs 214^e as shown in 60 Fig. 4. This will obviously prohibit any rearward movement of the detent strips and effectually lock the key-board. If no keys on the latter have been depressed none can be until the operation of the machine 65 through application of power thereto has

been completed. If keys have been depressed prior to such application of power the roll 228^d will pass farther down the abrupt front side of the lug 214^e of the detent strip associated with the depressed key of the bank, 70 thus maintaining this detent strip and the connected bell crank lever and stop rod locked against restoration to normal. This will be obvious from an inspection of Fig. 3.

The dotted lines at the left of Fig. 1 illustrate relative positions of parts when the point of the wipe-pawl 623^A is in contact with the roller 232 $\frac{1}{2}$. The key-releasing bail is of course then moved to the extreme of its forward excursion. This causes its cross-rod or bar 202 to cam the latching frame to its uppermost position, said rod or bar passing into contact with the under-edges of the side arms of said frame. This action lifts the roll 228^d entirely above all the lugs 214^e 80 and thus of course any displaced detent strip is freed from the restraint imposed upon it by said roll when standing in front of the forward edge of the lug 214^e. As before explained when the wipe-pawl 623^A passes up and out of contact with the roller 232 $\frac{1}{2}$ the spring 281 is permitted to draw the bail rearwardly until the roller 232 $\frac{1}{2}$ abuts the said wipe-pawl. This action carries the cross-rod or bar 202 back from under the 85 latching frame so that the latter may lower to a limited extent as the incline of the rear edges of its side arms permits, thus positioning the roll 228^d to be acted upon by the lugs 214^e in the manner already described. 90

It will now be seen that the objects primarily stated are thoroughly fulfilled by the above-described construction. It is, however, to be understood that such construction is susceptible of various modifications 95 within the scope of the invention.

What is claimed is:

1. In a machine of the character described, the combination of keys having catches or detents, a latch common to them and adapted to engage and detain any one of them, said latch capable of further movement to lock unoperated keys, and latch-controlling and actuating means normally maintaining the latch in position to permit operation of any key but adapted initially to permit locking movement of the latch. 110

2. In a machine of the character described, the combination of a group of keys, a group of detents, one for each key, a latch common to the detents and movable independently of key movement to lock the keys in normal position, and means for automatically lifting the latch to free any operated keys, with provisions for maintaining the latch normally out of locking position but in position to engage and detain any key detent. 115

3. In a machine of the character described, the combination of a group of keys, a group of detents, one for each key, a latch com- 120

mon to the detents and movable to lock the same in normal position, a reciprocatory latch actuator adapted at one extreme of its movement to lift the latch clear of the detents and at the other extreme of its movement to permit the latch to assume locking position with relation to the detents, and means for reciprocating said actuator with provisions for normally maintaining it at an intermediate position to hold the latch out of locking position but in position to be displaced by the detents.

4. In a machine of the character described, the combination of a group of keys, 15 detent strips severally connected therewith for longitudinal movement thereby and grouped side by side, said strips having alined projections, a latch having a part for said projections to act upon in displacing 20 the latch, the latter being movable to prevent such displacement, a latch actuator which at one end of its stroke permits the latter movement of the latch and at the other end of its stroke carries the latch clear 25 of the detent projections, and means for reciprocating said actuator with provisions for normally maintaining it at an intermediate position to hold the latch out of locking position but in position to be displaced 30 by the detent projections.

5. In a machine of the character described, the combination of a group of keys, a group of detents, one for each key, a latch common to the detents and movable to lock 35 the same in normal position, a reciprocatory latch actuator adapted at one extreme of its movement to lift the latch clear of the detents and at the other extreme of its movement to permit the latch to assume locking 40 position with relation to the detents, a spring for effecting the latter movement of the actuator, and means for moving the actuator in opposition to the spring to the first-named extreme, with provision for then 45 permitting partial return of the actuator and its maintenance at an intermediate position to normally hold the latch out of locking position but in position to be displaced by the detents.

50 6. In a machine of the character described, the combination of a group of keys, detent strips severally connected therewith for longitudinal movement thereby and grouped side by side, said strips having 55 alined projections, a latch having a part for said projections to act upon in displacing the latch, the latter being movable to prevent such displacement, a latch actuator which at one end of its stroke permits the 60 latter movement of the latch and at the other end of its stroke carries the latch clear of the detent projections, a spring for effecting the first-mentioned stroke of the actuator, and means effecting the full reverse 65 stroke in opposition to the spring, with pro-

vision for then permitting partial return of the actuator and its maintenance at an intermediate position to normally hold the latch out of locking position but in position to be displaced by the detent projections.

7. In a machine of the character described, the combination of a group of keys, a group of detents, one for each key, a latch common to the detents and movable to lock the same in normal position, a reciprocatory 75 latch actuator adapted at one extreme of its movement to lift the latch clear of the detents and at the other extreme of its movement to permit the latch to assume locking position with relation to the detents, said 80 actuator having stepped bearings, a driving member to move the actuator to the limit of its throw by action against one of said bearings, and a spring operating to partially retract the actuator bringing its other bearing 85 against the driving member to hold the latch normally out of locking position but in position to be displaced by the detents, said spring further acting, upon retraction of the driving member, to fully withdraw the actuator 90 and permit the latch to assume locking position.

8. In a machine of the character described, the combination of a group of keys, 95 detent strips severally connected therewith for longitudinal movement thereby and grouped side by side, said strips having alined projections, a latch having a part for said projections to act upon in displacing the latch, the latter being movable to prevent such displacement, a latch actuator which at one end of its stroke permits the latter movement of the latch and at the other end of its stroke carries the latch clear 100 of the detent projections, said actuator having stepped bearings, a driving member to move the actuator to the limit of its throw by action against one of said bearings, and a spring operating to partially retract the actuator bringing its other bearing against 105 the driving member to hold the latch normally out of locking position but in position to be displaced by the detent projections, said spring further acting, upon retraction of the driving member, to fully withdraw 110 the actuator and permit the latch to assume locking position.

9. In a machine of the character described, the combination of a row of de- 120 pressible keys, a group of longitudinally movable detent strips graduated in length and set on edge side by side with alined offset portions connected to the keys respectively, said strips having alining cam-lugs, a latch coöperating with the latter, and 125 means for operating the latch.

10. In a machine of the character described, the combination of a row of de- 130 pressible keys, a group of longitudinally movable detent strips graduated in length

and set on edge side by side with offset portions connected to the keys respectively, a latch common to the detent strips and movable to lock the same in normal position, a 5 reciprocatory latch actuator adapted at one extreme of its movement to lift the latch clear of the detent strips and at the other extreme of its movement to permit the latch to assume locking position with relation to 10 the detent strips, and means for reciprocating said actuator with provisions for normally maintaining it at an intermediate position to hold the latch out of locking position but in position to be displaced by the 15 detent strips.

11. In a machine of the character described, the combination of a row of depressible keys, a group of longitudinally movable detent strips graduated in length and set 20 on edge side by side with offset portions connected to the keys respectively, said strips having alining cam-lugs, a latch having a part for said cam-lugs to act upon in displacing the latch, the latter being 25 movable to prevent such displacement, a latch actuator which at one end of its stroke permits the latter movement of the latch and at the other end of its stroke carries the latch clear of the cam-lugs, and means 30 for reciprocating said actuator with provisions for normally maintaining it at an intermediate position to hold the latch out of locking position but in position to be displaced by the cam-lugs.

35 12. In a machine of the character described, the combination of a row of depressible keys, a group of longitudinally movable detent strips graduated in length and set on edge side by side with offset portions 40 connected to the keys respectively, a latch common to the detent strips and movable to lock the same in normal position, a reciprocatory latch actuator adapted at one extreme of its movement to lift the latch clear of the detent strips and at the other extreme of its movement to permit the latch to assume locking position with relation to the detent strips, a spring for effecting 45 the latter movement of the actuator, and means 50 for moving the actuator in opposition to the spring to the first-named extreme, with provision for then permitting partial return of the actuator and its maintenance at an intermediate position to normally hold the latch out of locking position but in position 55 to be displaced by the detent strips.

60 13. In a machine of the character described, the combination of a row of depressible keys, a group of longitudinally movable detent strips graduated in length and set on edge side by side with offset portions 65 connected to the keys respectively, said strips having alining cam-lugs, a latch having a part for said cam-lugs to act upon in displacing the latch, the latter being

movable to prevent such displacement, a latch actuator which at one end of its stroke permits the latter movement of the latch and at the other end of its stroke carries the latch clear of the cam-lugs, a spring for 70 effecting the first-mentioned stroke of the actuator, and means effecting the full reverse stroke in opposition to the spring, with provision for then permitting partial return of the actuator and its maintenance 75 at an intermediate position to normally hold the latch out of locking position but in position to be displaced by the cam-lugs.

14. In a machine of the character described, the combination of a row of depressible keys, a group of longitudinally movable detent strips graduated in length and set on edge side by side with offset portions connected to the keys respectively, a latch common to the detent strips and movable to lock the same in normal position, a reciprocatory latch actuator adapted at one extreme of its movement to lift the latch clear of the detent strips, and at the other extreme of its movement to permit the latch to assume locking position with relation to the detent strips, said actuator having stepped bearings, a driving member to move the actuator to the limit of its throw by action against one of said bearings, and a spring 80 operating to partially retract the actuator bringing its other bearing against the driving member to hold the latch normally out of locking position but in position to be displaced by the detent strips, said spring 85 further acting, upon retraction of the driving member, to fully withdraw the actuator and permit the latch to assume locking position.

15. In a machine of the character described, the combination of a row of depressible keys, a group of longitudinally movable detent strips graduated in length and set on edge side by side with offset portions connected to the keys respectively, said strips having alining cam-lugs, a latch having a part for said cam-lugs to act upon in displacing the latch, the latter being movable to prevent such displacement, a latch actuator which at one end of its stroke permits the latter movement of the latch and at the other end of its stroke carries the latch clear of the cam-lugs, said actuator having stepped bearings, a driving member to move the actuator to the limit of its throw by action against one of said bearings, and a spring operating to partially retract the actuator bringing its other bearing against the driving member to hold the latch normally out of locking position but in position to be displaced by the cam-lugs, said spring further acting, upon retraction of the driving member, to fully withdraw the actuator and permit the latch to assume locking position.

16. In a machine of the character described, the combination of a row of depressible keys, a group of longitudinally movable detent strips graduated in length and set on edge side by side with alined off-set portions, bell crank levers pivoted to the alined off-set portions of the strips respectively and engaged with the keys respectively, a latch coöperating with said strips, and means for operating the latch. 10 JESSE G. VINCENT.
